DOOR CLOSING HANDLE

Filed June 19 1926

W. M. Archibald

Watson E. Coleman
Attorney

UNITED STATES PATENT OFFICE.

WILLIAM M. ARCHIBALD, OF JACKSONVILLE, FLORIDA.

DOOR-CLOSING HANDLE.

Application filed June 19, 1926. Serial No. 117,160.

This invention relates to door closers and more particularly to a manually operated attachment for the doors of automobiles permitting closing of these doors without the necessity of reaching out of the car.

As is well known, the doors of automobiles open outwardly and in leaving a car, a person will often leave the door open, making it necessary for the driver of the car to reach out of the car to close the same. As these doors are relatively heavy, a grip must be taken on the door at a point well spaced from the hinge, with the result that during rainy weather, the occupant who is closing the door is often wetted. Accordingly, an important object of the invention is to provide an attachment for the door having an operating handle arranged adjacent the door hinge, so that it is practically accessible from the interior of the car without reaching therefrom and having a connection with the door at a point well spaced from the hinge, so that sufficient force may be applied to close the door without the exertion of an unnecessary amount of energy.

A further object of the invention is to provide a device of this character which may be either built into the new cars or attached to cars now in use and in which the handle will at all times be so positioned that it is unobtrusive while still readily accessible.

A further object of the invention is to provide a device of this character applicable to the doors of either closed or open cars, which will be durable and efficient in service, attractive in appearance and a general improvement in the art.

These and other objects I attain by the construction shown in the accompanying drawings, wherein for the purpose of illustration is shown a preferred embodiment of my invention and wherein:—

Figure 1 is an inside elevation of a portion of an automobile door having a closing handle constructed in accordance with my invention applied thereto;

Figure 2 is an enlarged transverse sectional view through the door on the line 2—2 of Figure 1, showing the handle in position thereon, the handle being illustrated in dotted lines in the position to which it may be shifted to apply leverage to the door to close the same;

Figure 3 is a section on the line 3—3 of Figure 2;

Figure 4 is an inside elevation of a modified form of attachment;

Figure 5 is a section on the line 5—5 of Figure 4;

Figure 6 is a fragmentary sectional view showing the manner in which the attachment may be disposed within a socket formed in the upper surface of the lower sill of a closed car or the upper end of the door of an open car;

Figure 7 is an enlarged sectional view on the line 7—7 of Figure 3.

Referring now to the drawings, the device consists essentially of a mounting bracket 10 adapted to be secured to the car door 11 adjacent the center thereof and having pivoted thereto a horizontally swinging arm 12, the terminal portion of which is formed as a handle 13 arranged adjacent the hinged side 14 of the car door. The bracket 10 and portion 18 of the arm 12 associated therewith are connected by a torsion spring 15, the function of which is to maintain the handle 13 against the inner face of the door when not in use.

The attaching bracket is in the form of a U-shaped member, in the arms 16 of which are formed aligned openings 17 through which a downturned end portion 18 of the horizontally directed arm is extended. About this downturned end portion, the torsion spring 15 is coiled, one end 19 of the spring bearing against the bight 20 of the U-shaped member while the other end thereof engages in a socket 21 formed in the downturned end portion 18, as more clearly shown in Figure 7. The method of attaching this bracket to the door of the car may be varied considerably.

In Figures 1, 2 and 3, one arm 16 of the bracket is provided with an extension 17 adapted to overlie the upper surface of the lower sill 22 of a closed car door having a vertically sliding glass 23 operating in a slot 24. The end of this extension is preferably provided with a downturned end portion 25 engaging in the slot between the portion of the sill lying inwardly of the glass and the glass. This extension may be formed with a slot 26 for the passage of a securing element 27 or the bight 20 may be formed with openings 28 for the passage of securing elements. In the form shown in

Figures 4 and 5, the arms 16 abut the inner face of the door with their ends and the securing elements 28 are directed through openings formed in the bight portion. In the form shown in Figure 6, a vertically extending socket 29 is formed in the door which houses the bight portion and one arm of the U-shaped member. The second arm is provided with extenfions 30 at its sides abutting the upper surface of the door about the edges of the socket and securing elements 31 are directed through openings formed in these extensions.

Attention is directed to the fact that in each of the constructions, that end of the spring which is extended through the downturned end portion of the shaft is extended therethrough immediately below the upper arm 16 of the bracket, so that this end of the spring serves not only to anchor the spring to the shaft but also as a pin or stop effectually preventing elevation of the arm 12 to an extent where the lower end of the downturned end portion 18 can be disengaged from the opening of the lower arm 16 of the bracket. Attention is further directed to the fact that the structure hereinbefore recited is such that it may be readily attached to doors without regard to which side of the door the hinges may be arranged upon. It is simply necessary to reverse the spring in its engagement with the bight to hold the handled end of the lever against the door at either side of the bracket. This eliminates all necessity for producing a device in rights and lefts which thereby materially reduces the cost of manufacture.

It will be obvious that other means of attaching the bracket might be resorted to without in any manner departing from the spirit of my invention and that other changes might be likewise made in the structure herein illustrated. I accordingly do not limit myself to such specific structure except as hereinafter claimed.

I claim:—

1. The combination with a vehicle door hinged along one side of the body of the vehicle, a bracket attached to the door adjacent the center thereof, a horizontally swinging arm pivoted to the bracket and having one end thereof extended adjacent the hinged edge of the door and provided with a handle, the bracket and arm being connected by a torsion spring urging the handled end of the arm into engagement with the inner face of the door, said bracket being U-shaped and having vertically aligned openings formed in the arms thereof through which a downturned extension upon the inner end of the arm is directed, said torsion spring being coiled about the downturned extension of the arm between the arms of the bracket and having one end thereof abutted against the bight of the bracket and the op-

posite end thereof secured to the downturned extension of the arm.

2. The combination with a vehicle door hinged along one side to the body of the vehicle, a bracket attached to the door adjacent the center thereof, a horizontally swinging arm pivoted to the bracket and having one end thereof extended adjacent the hinged edge of the door and provided with a handle, the bracket and arm being connected by a torsion spring urging the handled end of the arm into engagement with the inner face of the door, said bracket being U-shaped and having vertically aligned openings formed in the arms thereof through which a downturned extension upon the inner end of the arm is directed, said torsion spring being coiled about the downturned extension of the arm between the arms of the bracket and having one end thereof abutted against the bight of the bracket and the opposite end thereof secured to the downturned extension of the arm, one of the arms of said U-shaped member having a portion abutting the upper face of the door structure and adapted for the passage of securing elements.

3. The combination with a vehicle door hinged along one side to the body of the vehicle, a bracket attached to the door, a horizontally swinging arm pivoted to the bracket and having one end thereof extended adjacent the hinged edge of the door and provided with a handle and a spring for maintaining the handled end of the arm normally in engagement with the inner face of the door.

4. The combination with a vehicle door hinged along one side to the body of the vehicle, a bracket attached to the door adjacent the center thereof, a horizontally swinging arm pivoted to the bracket and having one end thereof extended adjacent the hinged edge of the door and provided with a handle, the bracket and arm being connected by a torsion spring urging the handled end of the arm into engagement with the inner face of the door, said bracket being U-shaped and having vertically aligned openings formed in the arms thereof through which a downturned extension upon the inner end of the arm is directed, said torsion spring being coiled about the downturned extension of the arm between the arms of the bracket and having one end thereof abutted against the bight of the bracket and the opposite end thereof extended through an opening formed in the downturned extension of the arm immediately adjacent the inner face of the arm of the bracket adjacent which the horizontally swinging arm operates.

In testimony whereof I hereunto affix my signature.

WILLIAM M. ARCHIBALD.
